METHOD OF SEASONING WOOD

James R. Nelson, Metropolis, Ill.

No Drawing. Application March 30, 1934,
Serial No. 718,205

8 Claims.

(Cl. 21-9)

This invention relates to patent-class of wood-preserving, and especially to an improved method for seasoning wood for impregnating purposes. To avoid confusion in the use of the words "timbers (timber)," "lumber," and "wood" it should be understood that the invention is applicable to logs, poles, ties, sawed or hewed beams, chunks, boards, strips or shingles of wood; and while it is not needed for firewood, the term "wood" is chosen as the broad or inclusive word to be hereinafter used to cover the field of usefulness of the invention, whether the wood be quite green or partially seasoned.

One object of the invention is to provide a method and means for seasoning wood much more quickly and uniformly than has heretofore been accomplished without cracking or checking the wood.

Another object is to provide a method for utilizing a fire-retardent solution as a medium of seasoning wood.

Another object is to provide a method for utilizing timber-preservatives or decay-retardents in liquid state as a medium of seasoning wood.

Another object is to provide a method for utilizing liquids or fluids as a medium of transmitting heat in this method of seasoning wood.

Another object is to provide a method whereby wood can be seasoned uniformly from the exterior surfaces to the innermost parts of the wood, even when the wood is in large and thick pieces.

Another object is to provide a method whereby any desired part of the moisture in wood can be removed uniformly from the exterior and interior alike without detriment to the wood.

Another object is to provide a method whereby the amount of moisture removed from the wood can be ascertained to facilitate knowledge as to what degree the wood is seasoned.

Another object is to provide a method for seasoning wood uniformly and to the desired extent, so that it can be impregnated with liquid (oil, tar or solution) preservative or fire-retardant.

Another object is to provide a method whereby wood preserving or other apparatus can be used and steps can be carried out by the alternative or successive application of pressure and vacuum in connection with the application of hot liquid in which the wood is immersed.

Before describing the method, it may be well to mention, in detail, some of the numerous fire-retardents and decay-retardents that may be employed in this method for seasoning woods of

various kinds and in various stages from green to partially seasoned:

Among the decay-retardents are:

Creosote or creosote oil,
Coal-tar or coke-oven-tar,

Water-gas-tar,

Crude petroleum or derivatives therefrom,
Mixture or solution of two or more of these.

Among the decay and fire-retardents, one or the other, or both are:

Zinc-chloride,

Mercuric chloride,

Sodium-fluoride,

Arsenic,

Borax,

Salts of various kinds.

For utilizing these or other preservatives in this method, they must be in liquid form, that is, the tars must be melted, and the salts must be in solution; but the seasoning (without preserving) may be effected by the use of pure water or other liquid, so the term "liquid" will hereinafter be used as broadly stating any liquid or fluid that is applicable in the method and capable of producing the desired result in presence of sufficient heat and pressure, and followed by vacuum, in the manner presently described. The term "liquid" also includes mixtures of these respective fire-retardents and decay-retardents, or with others not herein mentioned.

It is generally conceded by wood preservers that 260 degrees Fahrenheit temperature, or slightly more than 20 pounds steam pressure, is not injurious to any of the treatable woods, while some can stand 274 degrees F., or 30 pounds pressure.

The standard practice of steaming wood over long periods to heat it for artificial seasoning so that it can be impregnated, saturates the wood to maximum absorption, thus leaving a great deal of moisture in the wood when all heat is dissipated after releasing the steam pressure and creating vacuum.

In my method, no moisture is added to the wood when using oils or tars as the transmitter of heat, and air pressure is first used to fill the pores of the wood for retarding absorption, whereupon aqueous solutions are used as the transmitter of heat.

The theory of my method is to store heat units in the moisture-containing wood held under surrounding pressure, next to dissipate the heat units as latent heat, in the volatilization of moisture by releasing the said pressure, and immediately thereafter to create a vacuum around the wood.

In a simple and broad sense, the invention con-

sists in the following steps: (1) Immersing or submerging moisture-containing wood in an appropriate liquid, (2) applying sufficient heat and pressure to the liquid to thoroughly heat the wood to a sufficiently high temperature to volatilize a considerable part of the moisture within the wood when released to normal or atmospheric pressure, (3) separating the submerging liquid from the wood, and (4) subjecting the thoroughly heated wood to surrounding air that is sufficiently rarified to volatilize the remaining moisture of the wood, so as to season the wood uniformly throughout and to facilitate knowledge as to what degree the wood is seasoned, the moisture volatilized from the wood can be condensed and measured.

The above defined simple method is economically and conveniently effected in apparatus commonly used for pressure treatment of timber, consisting of a retort in combination with mechanical means to introduce the submerging liquid, to apply pressure thereto, to apply heat thereto, to compress air within the retort, to rarify the air therein, and to condense the moisture volatilized therein.

When wood is partially seasoned, or when at any time it is desirable to retard absorption, by the wood, of the heating liquid, initial air pressure should be applied to the wood within the retort, thus filling the pores of the wood with compressed air, and as the liquid is introduced, the surplus air is released at a retarded rate to maintain the desired pressure around and within the wood. When the retort is filled with the liquid, it is sealed to maintain the desired pressure, and heat is applied to the liquid through steam coils or other appropriate means and thus, through the heating period, both temperature and pressure are maintained at desired predetermined degrees until the timber is heated throughout to a temperature sufficiently high to volatilize a desired part of the moisture in the wood when the pressure is released. After the submerging liquid is removed from the retort, generated steam is allowed to pass off, thus dissipating all temperature in excess of 212 degrees Fahrenheit. By means of any appropriate apparatus, vacuum is next created and maintained in the retort over the wood and liquid, and as the moisture in the wood is volatilized, more heat is dissipated as vacuum is increased by operation of said apparatus, thus lowering the boiling point more and more until when 24 inches of vacuum is recorded, whereat water boils at 140.6 degrees F.; so, at 26 inch vacuum the moisture is volatilized at 125.4 degrees F.; at 27 inch vacuum, at 115 degrees F.; and at 28 inch vacuum, at 100 degrees F.

In the manner explained above, the heat stored up in the wood, during the heating period or step, is used in volatilizing the moisture therein when pressure is released and vacuum is created, thus seasoning the interior and exterior of each piece of timber or wood in direct proportion to the amount of heat stored and dissipated.

It is essential to maintain and control sufficient pressure around the wood to prevent volatilization of moisture therein during the heating period and until the timber is thoroughly heated to and through its center, as lack of pressure would not only allow dissipation of heat, but also allow removal of moisture from exterior surfaces of the wood before its center is heated, which in turn would cause checks and cracks in the exterior surfaces in consequence of shrink-

age being greater at the exterior than at the interior or center.

I accomplish the desired results in this method by operation as follows:

Starting either with or without initial air pressure in the retort in which the wood is being seasoned, the wood is submerged in liquid and the submerging liquid is heated to a predetermined temperature with pressure maintained sufficient to prevent moisture from volatilizing for a predetermined period, according to the kind of wood, the size of the pieces, and the moisture content of the wood. Next, separate the liquid from the wood and release the pressure, thus letting stored heat in the wood in excess of boiling temperature at atmospheric pressure be dissipated by volatilizing moisture from the wood, which moisture passes off as vapor and can be condensed if desired. Next create and maintain vacuum over the moisture-containing wood within the retort and thereby dissipate as much of the remaining stored heat as is possible or desirable by volatilization of moisture in the wood through low boiling temperatures of vacuum.

By the above described method, the center and surface of the wood are simultaneously seasoned, that is, the wood is seasoned uniformly throughout and is susceptible to impregnation with fluid preservatives, in volume as great as, or greater than that of the moisture extracted, and preservative fluid can be distributed to the innermost parts of the wood from whence the moisture was volatilized.

I have no intention to limit my patent protection to the precise details given in the foregoing, for the invention is susceptible of numerous changes within the scope of the inventive ideas herein implied and claimed.

What I claim as my invention is:

1. The wood-seasoning method which includes submerging moisture-containing wood in suitable liquid under adequate pressure initially to prevent volatilization, applying and maintaining sufficient heat to the liquid to thoroughly heat the wood throughout to a sufficiently high temperature to volatilize a considerable or desired part of the moisture in the wood when in atmospheric pressure and separated from the submerging liquid, and thereafter subjecting the wood to surrounding air which is continually kept sufficiently rarified below normal atmospheric pressure to volatilize a desired or substantial part of the moisture in the wood.

2. The wood-seasoning method which includes submerging moisture-containing wood in suitable liquid under adequate pressure initially to prevent volatilization, applying and maintaining sufficient heat to the liquid to thoroughly heat the wood throughout to a sufficiently high temperature to volatilize some of the moisture of the wood when separated from the submerging liquid and allowed to stand at atmospheric pressure, and thereafter subjecting the still-hot wood to surrounding air which is continually kept sufficiently rarified to volatilize a considerable or desired part of the moisture remaining in the wood.

3. The wood-seasoning method which includes submerging moisture-containing wood in a suitable liquid under adequate pressure initially to prevent volatilization, applying heat to the liquid without applying pressure other than that of heat-expansion, maintaining the heat at a sufficiently high temperature to thoroughly heat the wood throughout sufficiently to volatilize moisture and liquid in the wood when the pressure is re-

duced to atmospheric pressure, separating the submerging liquid from the wood, and thereafter subjecting the thoroughly heated wood to surrounding air that is continually kept rarified below normal atmospheric pressure, until a desired or substantial part of the moisture in the wood is volatilized.

4. The wood-seasoning method which includes submerging moisture-containing wood in suitable liquid under adequate pressure to prevent volatilization, adding sufficient pressure to the liquid for driving part of the liquid into the wood while raising the temperature of the liquid and wood, applying heat to the liquid in addition to that caused by the pressure, maintaining the heat at a sufficiently high temperature to volatilize a considerable part of the wood's inherent moisture and applied liquid when released to atmospheric pressure, separating the submerging hot liquid from the wood, thereafter subjecting the thoroughly heated wood to atmospheric pressure and thereby volatilizing a part of the moisture, and thereafter subjecting the still-hot wood to surrounding air which is kept continually rarified below atmospheric pressure until a desired part or substantially all of the remaining moisture in the wood is volatilized.

5. The wood-seasoning method which includes impregnating moisture-containing wood with compressed air, submerging the air-impregnated wood in a suitable liquid under slightly greater pressure than that of the initial compressed air and thereby driving part of the liquid into the wood to sufficient depth to increase compression of the compressed air in the pores of the wood and thereby intensifying the heat, applying heat to the liquid besides the heat of compression, and maintaining the heat at a sufficiently high temperature to volatilize moisture and liquid in the wood when the pressure is reduced to atmospheric pressure, separating the submerging liquid from the wood, releasing the pressure for permitting the compressed air in the wood to force out some of the liquid which has entered the outer surfaces, and thereafter subjecting the air-impregnated and thoroughly heated wood to surrounding air sufficiently rarified below normal atmospheric pressure to volatilize the desired part or substantially all of the remaining moisture and liquid in the wood.

6. The method of seasoning wood and impregnating the outer surface of the wood with wood-preserving material, which method comprises submerging the wood in a volatile liquid which includes or constitutes the wood preserving material, applying sufficient pressure to the liquid to prevent initial volatilization, applying sufficient heat to the liquid to thoroughly heat the wood throughout to sufficiently high temperature to

volatilize part of the moisture at atmospheric pressure, after separating the submerging liquid from the wood, and thereafter subjecting the heated and partially impregnated wood to surrounding air that is continually kept sufficiently rarified to volatilize a considerable part of the volatile constituent of the liquid and a desired part of the moisture in the wood and to leave a part of the non-volatile constituent within the wood for preserving the wood.

7. The herein described wood-seasoning method which comprises partial or slight impregnation of wood with liquid which includes volatile and non-volatile constituents which are combined to form a wood preservative, applying to the partially or slightly impregnated wood a sufficient pressure to prevent initial volatilization of the liquid and also applying sufficient heat to saturate the wood so as to volatilize a considerable part of the volatile constituent when the pressure is reduced to normal atmospheric pressure, separating the wood from the submerging liquid, and subjecting the hot wood to surrounding air which is continually kept sufficiently rarified a sufficient time to volatilize approximately all of the remaining volatile constituent and moisture in the wood, leaving the non-volatile constituent precipitated in the wood as a preservative.

8. The herein described method of seasoning green or semigreen wood for impregnating purposes, using hot preservative liquids in contact with the wood as the medium of transmitting heat to the wood; which method includes applying compressed air in the pores of the wood to retard the absorption of the liquid during the heating period, submerging the air-impregnated wood with the heating liquid, applying heat to the liquid and applying force to the liquid to subject it to pressure to maintain the compressed air in the pores of the wood and to intensify the heat and for avoiding dissipation of heat through volatilization during the heating period, discharging the heating liquid from around the wood, maintaining air pressure on the wood while the liquid is being discharged, reducing air pressure to normal atmospheric pressure and thus discharging air and liquid and volatilized moisture from the wood by the air pressure in the pores of the wood, creating vacuum around the wood so as to volatilize moisture at subnormal atmospheric boiling temperature until volatilization of moisture has dissipated substantially all of the heat stored in the wood during the heating period, condensing the volatilized moisture and measuring the condensed moisture volatilized from the wood to facilitate knowledge as to what degree the wood is seasoned.

JAMES R. HELSON.
